UNITED STATES PATENT OFFICE.

CLARENCE E. NORTON, OF GUILFORD, CONNECTICUT, ASSIGNOR OF ONE-HALF TO
ROBERT G. MITCHELL, OF MOUNT VERNON, NEW YORK.

SHEARS.

Application filed September 16, 1925. Serial No. 56,586.

This invention relates to improvements in tools for cutting strap iron and the like, the construction being such that the cutting operation may be performed in very inaccessible places where ordinary shears cannot be easily or successfully employed.

Among the objects are simplicity of construction, cheapness of manufacture and efficiency of operation.

10 In the accompanying drawings—

Fig. 1 is a perspective view of my invention in position for use;

Fig. 2 is a relatively enlarged view of the parts constituting my invention as in operation, portions being broken away.

15 1—2 represent blades. Each of said blades has a relatively short longitudinal slot in its end. These slots are of substantially the same size. 3 is what I will term a "blade holder", the same comprising a strip of metal having a slot at the end of sufficient width to receive between the bifurcated ends formed of the two blades 1—2, so as to hold the sides of said blades closely together.

20 This means constitutes in effect a yoke but different from a pivot bolt such as used in ordinary shears, it leaves one blade free to slide on the other and does not constitute a fixed connecting fulcrum as in the case of the pivot bolt.

25 I have shown my invention as employed in cutting one of the brake straps in a transmission gear such as used in a "Ford" automobile. 4 represents the housing for said transmission gear, and 5 represents a metallic brake strap provided with the usual brake lining 6, such as used in such gears. These straps are provided with head pieces 30 secured at the ends thereof, one of which appears at 7.

35 When it is necessary to reline or replace a Ford transmission brake strap it is necessary to remove the old strap from the housing 4. Since ordinarily the heads 7 are riveted on, and since there is insufficient clearance to pull out one of the straps without removing one head 7, it is necessary to break off the strap unless the head is first removed, 40 and this is a tedious and difficult job. It is furthermore difficult to sever the strap by any ordinary cutting device, such as a pair of shears. By my improved cutting tool this severing operation of the strap 5 is

45 easily and quickly performed by simply freeing the brake strap, pulling one end partially around in the housing, as shown, and applying the two blades 1—2 thereto, as indicated in Fig. 1, wherein the strap 5 stands in the slotted ends of the two blades. The 50 blade holder 3 may then be applied as shown, so as to hold the blades 1—2 closely adjacent to one another, whereby when the outer ends of the blades 1—2 are brought together, the edges of the slots in which the 55 strap 5 stands operate to quickly cut the strap 5, the strap itself acting as the fulcrum on which the blades 1—2 turn. By this operation said strip or strap 5 will be sheared, as indicated in Fig. 2 by the solid 60 and dotted lines, so that the two ends may then be removed from the housing 4. By this arrangement an exceedingly powerful leverage is obtained, as compared with the ordinary shears wherein the pivot which forms 65 the fulcrum would stand at a considerable distance from the strap 5, thereby requiring much more power to operate the cutting means.

70 It is preferred to pitch slots in the ends of the blades 1 and 2 at a convenient angle relatively to the upper and lower edges of said blades so that the lower side of each blade end may be entered readily under the strap, and also so that when the strap is 75 in place in the slots, the blades will stand at an angle to each other as indicated in the drawing, whereby by forcing the outer ends toward each other the strap will be 80 sheared.

85 What I claim is:

1. A cutting tool comprising two independent blades, each of the same having a slot in one end thereof forming complementary cutting edges, a yoke for holding 90 said blades in operative position side by side without penetrating the same.

2. A cutting tool comprising two independent blades, each of the same having a slot in one end thereof forming complementary cutting edges, and blade-holding means 100 freely engaging said blades for holding the same in operative position side by side, said means comprising a blade having a recess in its end to form shoulders engaging the 105 opposite outer sides of said cutting blades when the same are in cutting position.

CLARENCE E. NORTON,
